CONVERTIBLE GAME TABLE

Philip Zelkowitz, Lincolnwood, Ill., assignor to Armac
Enterprises, Inc., Chicago, Ill.

Filed July 24, 1972, Ser. No. 274,185

Term of patent 3½ years

Int. Cl. D6—03

U.S. Cl. D6—149

FIG. 1

FIG. 2

FIG. 3

FIG. 4

FIG. 6

FIG. 7

FIG. 5

FIG. 8

FIG. 1 shows a top plan view of a convertible game table in one of its aspects;

FIG. 2 shows a cross section taken on the line 2—2 of FIG. 1;

FIG. 3 is a view in side elevation of the table of FIG. 1 wherein the interchangeable top is added thereto;

FIG. 4 is a plan view of the table shown in FIG. 3;

FIG. 5 is a plan view of the table of FIG. 4 wherein the interchangeable top has been reversed;

FIG. 6 is a cross section taken on the line of 6—6 of FIG. 5;

FIG. 7 is a cross section taken on the line 7—7 of FIG. 5; and

FIG. 8 is a section taken on the line 8—8 of FIG. 3.

I claim:

The ornamental design for a convertible game table, as shown and described.
